LIGHT PROJECTOR

Edward J. Whalen, Syracuse, N. Y.

Application January 24, 1938, Serial No. 186,513

1 Claim. (CL 240—44.2)

This invention relates to light projectors or lamps, such as head lamps for motor vehicles, and the like, and has for its object a reflector construction comprising a main reflector zone and one or more circumferential auxiliary reflector zones, which reflect light rays back onto the central or main reflector zone, where they are projected out in the main beam.

It further has for its object a lamp socket and holder by which the lamp and lamp socket may be removed, as a unit, from the rear end of the reflector or the lamp, for the purpose of replacing a burned out lamp bulb.

The invention consists in the novel features and in the combinations and constructions hereinafter set forth and claimed.

In describing this invention, reference is had to the accompanying drawings in which like characters designate corresponding parts in all the views.

Figure 1 is a longitudinal sectional view of a lamp embodying this invention.

Figure 2 is an exploded view of parts seen in Figure 1, showing the construction by which the lamp bulb and holder are removable as a unit.

Figure 3 is a detail view of the support within the lamp for the parts seen in Figure 2.

1 designates the shell or casing of the lamp, which may be of any suitable form, size and construction, it having a glass or lens 2 at its front end. 3 designates the reflector as a whole. This includes a rear main zone or section 4, which is preferably parabolic or of such curvature as to project the light rays in nearly parallel lines as possible. It also includes one or more auxiliary reflectors, as 5 and 6, arranged one in front of the other in front of the focal plane P, these reflectors 5 and 6 being annular or extending circumferentially of the reflector and located outside of the path of the light rays of the main beam projected from the main reflector 4. The auxiliary reflectors 5 and 6 are spherically curved and of greater radius from the focus F than the main reflector and the front reflector 6 being of greater radius than the reflector 5. The reflector 3 is suitably mounted in the shell 1.

7 designates the lamp having a suitable filament, and 8 the base of the lamp. The lamp is so mounted that its source of light or filament is so located that the greatest portion thereof is as near as possible to the focus F. In order to effect this result, it is usually located slightly in advance of the focus F.

Some of the light rays projected directly from the source of light pass directly from the source

at different radial angles out through the lens 2. Other rays projected from the source of light pass at greater radial angles and strike the reflectors 5, 6. Other rays of light strike the main reflector 4 and are projected in nearly parallel lines therefrom to the lens 2.

It has been estimated that fifty percent of the light passes in a beam through the lens 2 either directly from the source of light or indirectly from the main reflector 4; that thirty-five percent of the light passes at such angles as to strike the reflectors 5, 6 and that with ordinary reflectors without the reflector zones 5, 6 is dissipated and uncontrollable; and that fifteen percent of the light rays are absorbed by the glass or lens 2.

The purpose of the auxiliary reflectors 5, 6 is to recover or control the thirty-five percent and redirect it back into the main beam.

In operation, the light rays strike the main reflector 4 and are projected outwardly in a beam of parallel lines or nearly parallel lines that the light rays striking the reflectors 5, 6 are reflected back onto the main reflector 4 and projected outwardly in the main beam in nearly parallel lines, so that eighty-five percent of the available light is collected in the main beam.

The means by which the lamp may be removed comprises a lamp socket 11 for receiving the base 8 of the lamp carriage including a tubular cup-shaped part 12 surrounding and rigid with the lamp socket 11 and telescoping with a complementary cup-shaped part 13 having a front wall 14 forming a continuation of the reflector 4 or forming the central portion of the reflector 4, 35 these parts being mounted in a tubular stem 15 extending coaxially of the casing 1 and secured thereto at 16, and also secured to the reflector 4 at 17. They are held in position by a cap 18 threading on the end of the stem 15 and pressing against a bracket 19 rigid with the cup-shaped part 12 of the carriage. A suitable cushion or gasket 20 is interposed between the cap 18 and the bracket 19. The lamp socket is adjustable axially by means of a screw 21 extending through the bracket 19 and threading in a lug 22 on the lamp socket 11, the screw having a suitable collar 23 thereon for holding it from endwise movement during turning thereof. The lamp socket is provided with suitable wire terminals 24 for the feed wires 25. The front end of the stem 15 is split or made expandable or contractile by splitting at 26 and is formed with a peripheral groove 27 for receiving the margin at 28 of the reflector zone 4.

This construction is such that the front end 55

of the tubular support 15 may be attached to the reflector zone 4 with a snap action.

After the bulb has been placed in position, the light may be focused by means of screw 21 before reapplying the cap 18.

What I claim is:

In a light projector, an outer shell, a reflector in the shell having a rearwardly extending tubular stem at the rear end thereof, the stem being secured to the rear end of the shell and projecting through the same, a lamp socket carriage including front and rear cup-shaped parts telescoping one within the other, the front part

having its bottom wall forming a continuation of the reflector zone, a lamp socket carried by the carriage, the tubular stem being of larger diameter than the lamp bulb to permit the lamp socket and lamp bulb to be removed as a unit with the carriage through the rear end of the reflector and the shell, means for adjusting the lamp socket axially of the carriage and the reflector and operable from the rear end of the tubular stem, and a retaining member on the projecting end of the tubular stem for holding the lamp socket and the carriage from displacement.

EDWARD J. WHALEN.
